(57) **CLAIM**

The ornamental design for a device holder, as shown and described.

DESCRIPTION

FIG. 1 is a front perspective view of the device holder showing my new design;

FIG. 2 is a rear perspective view thereof;

FIG. 3 is a front view thereof;

FIG. 4 is a rear view thereof;

FIG. 5 is a side view thereof;

FIG. 6 is an opposite side view thereof;

FIG. 7 is a top plan view thereof; and,

FIG. 8 is a bottom plan view.

The broken line showing of environment in the drawings is included for the purpose of illustrating only and forms no part of the claimed design.

1 Claim, 4 Drawing Sheets(56)
